US0D1053377S

(12) **United States Design Patent** (10) Patent No.: **US D1,053,377 S**
(45) Date of Patent: ** Dec. 3, 2024

(54) **DIAGNOSTIC ANALYZER UNIT**

(71) Applicant: **Siemens Healthcare Diagnostics Inc.**,
Tarrytown, NY (US)

(72) Inventors: **Youngsang Lee**, Bayside, NY (US);
Daniel LiCalzi, New York, NY (US);
Robert Faranda, Boxborough, MA
(US); **Eric Zhu**, Forest Hills, NY (US)

(73) Assignee: **Siemens Healthcare Diagnostics Inc.**,
Tarrytown, NY (US)

(**) Term: **15 Years**

(21) Appl. No.: **29/804,436**

(22) Filed: **Aug. 19, 2021**

(51) LOC (14) Cl. **24-02**

(52) U.S. Cl.

(57) **CLAIM**

The ornamental design for a diagnostic analyzer unit as shown and described.

DESCRIPTION

FIG. 1 is a perspective view of the diagnostic analyzer unit. FIG. 2 is a front view of the diagnostic analyzer unit. FIG. 3 is a back view of the diagnostic analyzer unit. FIG. 4 is a first side view of the diagnostic analyzer unit. FIG. 5 is a second side view of the diagnostic analyzer unit. FIG. 6 is a top view of the diagnostic analyzer unit; and, FIG. 7 is a bottom view of the diagnostic analyzer unit. In the drawings, the equal-length broken lines depict portions of the diagnostic analyzer unit that form no part of the claimed design.

1 Claim, 7 Drawing Sheets
